US00D731024S

(12) **United States Design Patent**
Elliott et al.

(10) **Patent No.:** **US D731,024 S**
(45) **Date of Patent:** **** Jun. 2, 2015**

(54) **PORTABLE BACTERIA DEACTIVATION DEVICE**

(71) Applicant: **Silver Aqua, Inc.**, Carlisle, MA (US)

(72) Inventors: **David J. Elliott**, Carlisle, MA (US); **Ronald P. Millman, Jr.**, Taunton, MA (US); **Amber P. Truhanovitch**, Webster, MA (US)

(73) Assignee: **Silver Aqua, Inc.**, Carlisle, MA (US)

(**) Term: **14 Years**

(21) Appl. No.: **29/475,554**

(22) Filed: **Dec. 4, 2013**

Related U.S. Application Data

(63) Continuation of application No. 29/436,720, filed on Nov. 8, 2012, now abandoned.

(57) **CLAIM**

The ornamental design for a portable bacteria deactivation device, as shown and described.

DESCRIPTION

FIG. 1 is an isometric view from the front of a portable bacteria deactivation device incorporating the design; FIG. 2 is a left-side view thereof; FIG. 3 is a right-side view thereof; FIG. 4 is a front view thereof; FIG. 5 is a back view thereof; FIG. 6 is a top plan view thereof; FIG. 7 is a bottom plan view thereof; FIG. 8 is an isometric view of an alternative embodiment; FIG. 9 is a top view of the alternative embodiment; FIG. 10 is a bottom view of the alternative embodiment; FIG. 11 shows the article worn on a neck chain; and, FIG. 12 shows the article being used to deactivate bacteria in a water bottle.
Parts of the drawings shown in dotted lines form no part of the claimed invention.

1 Claim, 10 Drawing Sheets
